CLAIM

The ornamental design for an actuator for a liquid dispenser, as shown and described.

DESCRIPTION

FIG. 1 is a perspective view of the actuator for a liquid dispenser showing my new design;
 FIG. 2 is a side elevation view;
 FIG. 3 is a top plan view;
 FIG. 4 is a rear elevational view;
 FIG. 5 is a front elevational view;
 FIG. 6 is a fragmentary view on an enlarged scale of a portion of the actuator shown in FIG. 5;
 FIG. 7 is a perspective view of a modified form of an actuator for a liquid dispenser showing my new design;
 FIG. 8 is a side elevational view;
 FIG. 9 is a top plan view;
 FIG. 10 is a rear elevational view;
 FIG. 11 is a front elevational view; and,
 FIG. 12 is a fragmentary view on an enlarged scale of a portion of the actuator shown in FIG. 11.
 The broken lines shown in FIGS. 1 and 7 are for illustrative purposes only and form no part of the claimed design.
